UNITED STATES PATENT OFFICE.

RICHARD W. RICH, OF WORCESTER, MASSACHUSETTS.

ICE-CUTTING MACHINE.

1,169,355.

Specification of Letters Patent. Patented Jan. 25, 1916.

Application filed June 4, 1914. Serial No. 843,069.

To all whom it may concern:

Be it known that I, RICHARD W. RICH, a citizen of the United States, residing at Worcester, in the county of Worcester and State of Massachusetts, have invented a new and useful Ice-Cutting Machine, of which the following is a specification.

This invention relates to an ice cutting machine and particularly to certain improvements in an ice cutting machine of the type shown in my pending application, Serial No. 742,882, filed January 18, 1913.

In the machine shown in the prior application I have provided a plurality of sets of saws, each set being positioned and operated at right angles to the preceding set. I have also provided guides for determining the line of travel of the floats and feeding devices for moving the floats or portions thereof past the several sets of saws. No provision is made, however, in my earlier machine for moving the floats from one feeding device to the next or for changing the direction of travel of the floats, this operation being performed by manual labor.

It is the principal object of my present invention to provide automatic devices for performing this latter operation, thus eliminating a large part of the manual labor required to operate my earlier machine.

The former method of moving the ice necessitated its manipulation in large floats and accordingly I could not completely sever the cakes but was obliged to leave webs joining the cakes together until the float had nearly completed its course through the machine. It was then necessary to employ a number of bar men to sever the floats into separate cakes.

The provision in my present machine of automatic devices for moving the ice permits me to completely sever the ice at each cut as the automatic devices are so arranged that a plurality of separate cakes may be transported and manipulated as an unit. The resulting elimination of the bar men still further reduces the element of manual labor and it also avoids the damage to the ice which is unavoidable when bars are used to separate the cakes.

Further objects of my invention will appear in the following specification and will

be more specifically pointed out in the appended claims.

A preferred form of my invention is shown in the drawings in which—

Figure 1 is a diagrammatic view showing the arrangement of my complete machine; Figs. 2, 3 and 4 show the float of ice at three different stages in its passage through the machine; Fig. 5 is a detail plan view showing a portion of the machine on an enlarged scale; Fig. 6 is a side elevation of the mechanism for driving the saws; Fig. 7 is a side elevation of the mechanism for driving the main feed shaft; Fig. 8 is a detail view of a portion of the conveying chains; and Fig. 9 is a plan view of certain of the driving parts shown in Fig. 1, drawn on enlarged scale.

As the proportions and arrangements of the several parts of my machine will vary to a certain extent in accordance with the size of the float and the number of cakes into which it is sub-divided, I have shown in Fig. 1, for purposes of illustration, a machine designed to receive floats of ice measuring 280" in each direction and to subdivide each float into 140 cakes, each measuring 20" x 28".

The floats are manually moved into position within the guideway 10 and are thereafter moved forward by the feeding chains 11. These chains are shown in detail in Fig. 8 and are provided at intervals with spurs 12 projecting therefrom. These spurs advance the float A (Fig. 2) to a line of saws 13 (Figs. 1 and 6) mounted upon a shaft 14 and driven by a motor M. A second line of saws 15 (Fig. 6) is mounted upon a shaft 16 also driven by the motor M.

While the connections between the motor and the saw shafts may be of any convenient form, I have indicated a simple arrangement in Figs. 5 and 6 in which the upper saw shaft 14 carries a spur gear 17 meshing with a gear 18 mounted upon the motor shaft m. The lower shaft 16 carries a sprocket 19 and is driven by a chain 20 from a sprocket wheel 21 upon the shaft m. In this manner the lines of saws are driven in opposite directions and each cuts against the float as it is moved forward by the feeding chains 11.

In its passage by the saws the float A is partially supported and laterally directed by a guideway comprising a slatted bottom 22 (Fig. 5) and sides 23. The slats of the bottom are arranged to allow the conveyer chains to operate through openings between the slats and the machine as a whole is so positioned with relation to the level of the water and the thickness of the ice that the float A is raised only slightly above its normal floating position as it passes along the guideway.

The chains 11 are driven by sprockets 24 (Fig. 5) fixed upon a transverse shaft 25 having a beveled gear 26 secured to one end thereof. The gear 26 meshes with a beveled pinion 27 upon a shaft 28 which is driven in turn through a pair of beveled gears 29 and 30 (Fig. 1) from the main shaft 31. The shaft 31 may be provided with a sprocket 32 (Fig. 7) driven by a chain 33 from a driving sprocket 34 secured to a countershaft 35. The counter shaft 35 is connected by a friction clutch 36 (Figs. 1 and 9) of any ordinary type with a cone pulley 37 loosely mounted on the shaft 35. The pulley 37 is belt driven from a cone pulley 38, mounted on a second countershaft 39 which also carries a gear 40 meshing with a pinion 41 on the shaft *p* of a motor P. With these connections it will be seen that the feeding chains 11 may be driven at any one of several different speeds and that they may be started and stopped at will by the use of the friction clutch 36. This clutch also provides a yielding connection in case the operation of the feeding chains is obstructed.

While the arrangements for driving the shaft 31 and the chains 11, as herein described are simple and effective any other convenient arrangement for accomplishing this result may be substituted therefor, as the driving and transmitting devices, *per se*, form no part of my invention.

In the case selected for illustration, the float A in passing the lines of saws 13 and 15 is divided into seven strips B each measuring 40" wide by 280" long. The strips B are then pushed forward over a set of conveyer chains 50, which are driven by sprockets mounted upon an extension of the main shaft 31. At their rear ends the chains 50 pass over the sprockets 51 (Fig. 5) which are loosely mounted upon the shaft 25 and are freely rotatable thereon.

Inspection of Fig. 1 will show that the shaft 31 rotates at twice the speed of the shaft 25 and as the chain driving sprockets are of the same size it follows that the conveyer chains 50 travel at twice the speed of the feeding chains 11.

A second set of conveyer chains 60 is mounted to run at right angles to the chains 50, being driven by sprockets secured

to a shaft 61 mounted at right angles to the main shaft 31 and driven at the same speed by beveled gears 62 and 63. At their rear ends the chains 60 pass over sprockets upon an idle shaft 64.

A second set of feeding chains 70 is mounted in advance of the chains 60 and is driven by sprockets upon a shaft 71 which is operated through beveled gears 72 and 73 from the shaft 31. The gear 72 is twice the diameter of the gear 73 and the shaft 71 thus rotates at one-half of the speed of the shaft 31, the speed of the shaft 71 being the same as that of the shaft 25.

The feeding chains 70 feed the strips B past a second set of saws 74, comprising upper and lower lines of saws corresponding to the saws 13 and 15 in the first mentioned set. This set of saws is driven by a motor M', the driving connections being the same as those previously described. In the illustrative machines, there are nine saws upon each shaft in the second set and these saws divide each strip B into ten double blocks C each measuring 28" wide by 40" long.

In order to transfer the float from the first set of saws to the second, it will be evident that the direction of travel of the floats must be changed by ninety degrees. This would be clearly impossible if the floats came forward in a continuous line upon the conveyer chains 50. I have called attention, however, to the fact that the chains 50 travel at twice the speed of the feeding chains 11. Each chain 50 carries two spurs 52 (Fig. 8) separated from each other by twice the width of the float A or by 560". As these spurs are separated by twice the space, but also travel at twice the speed of the spurs 12 on the chains 11, it will be evident that one set of spurs 52 will come into position as each float is advanced over the chain 50 by the slow moving spurs 12 on the chains 11 and that the floats as they are moved forward by the spurs 52 will be separated by a space between each two floats equal to the width of a float.

The conveyer chains 60 are similarly provided with two spurs upon each chain separated by twice the width of the float or 560". These chains move at the same speed as the chains 50. In this manner the chains 50 are able to advance the float A after it has been divided into strips B and to position it over the chains 60, which then move the float at right angles to its previous line of travel. The spaced relation of the floats enables this float to move transversely out of the path of the succeeding float as that float is projected over the chains 60.

The feeding chains 70 are each provided with similar spurs separated by intervals of 280" or the width of a float. These chains travel at one half of the speed of the chains 60 and accordingly advance a float 280" 130

while the chains 60 are advancing the next succeeding float 560" into position to be taken up by the next set of spurs on the chains 70. By this disposition of driving spurs and arrangement of relative speeds, I am enabled to advance the floats in spaced relation while changing their direction of travel and also to present the floats in a substantially continuous line to the saws 74.

10 In advance of the chains 70 I provide a set of chains 80 (Fig. 1) driven by sprockets upon a shaft 81 carrying a pinion 82, meshing with a beveled gear 83 upon the end of the main shaft 31. In the selected combination the gears 82 and 83 bear the ratio of 1 to 5.

Assuming a travel of one inch per second for the chains 11 and 70 and of two inches per second for the chains 50 and 60, 20 the chains 80 will have a speed of ten inches per second. These chains each carry a single spur and are of such length that this spur comes into operative position as each one of the strips B is projected over the chains 80 by the spurs upon the chains 70. The strips B are thus advanced in spaced relation by the chains 80 and are projected over a chain 90 running at right angles thereto and driven by a sprocket on a shaft 91 25 geared to a shaft 92 which in turn is driven by the main shaft 31. The shaft 92 is driven at twice the speed of the shaft 31 and the shaft 91 is driven at twice the speed of the shaft 92, this combination giving the chain 90 a travel of 8" per second. This chain carries two spurs which may conveniently be separated by something more than the length of a strip or 320".

A set of two chains 100 is positioned in 40 advance of the chain 90 and is driven by sprockets upon a shaft 101 driven in turn by beveled gears from the shaft 92. These gears bear the ratio of 7 to 4 giving the chains 100 a travel of seven inches per second. The latter chains carry the double 45 cakes C past a pair of saws 102, only the upper one of which is shown. These saws are driven from a motor M², the driving connections again being similar to those already 50 described for the motor M.

The relative speeds of the chains 80 and 90 are such that the strips B are advanced in spaced relation by the chains 80 and are each thereafter moved at right angles to 55 the previous direction of travel with sufficient rapidity to clear the next following strip B.

The speeds of the chains 90 and 100 are 60 so proportioned that each strip B will overtake the preceding strip as it is projected over the chain 100 so that the strips B composed of double blocks C will be fed in a substantially continuous line past the saws 102 and will be thereby separated into 65 blocks D, each measuring 20" wide by 28"

long. After passing the saws 102, the blocks are delivered upon a conveyer indicated diagrammatically at 110, which may be of any usual type and operates to transfer the separated cakes to storage.

In order to keep the severed strips or cakes in alignment as they are transferred from one set of saws to the next, I provide the spring-pressed guides 120 shown in Fig. 5. These guides are mounted upon one side of the guideway and press the ice yieldingly against the opposite side of the guideway, thereby alining the cakes and preventing their displacement during transfer.

In my previous application I have shown 80 similar guides for controlling the ice as it passes the saws and such guides may also be used in my present machine but have been omitted to avoid complications in the drawings.

From the foregoing description it will appear that I have provided an entirely automatic ice cutting machine having its several parts so proportioned and operated that the ice is presented in a substantially continuous line to each of three sets of saws 90 but nevertheless has its direction of travel changed automatically by 90 degrees between each two sets of saws.

The three sets of saws may if desired be 95 driven by a single motor but the arrangement indicated is more easily adapted to different conditions. It is essential, however, that all of the conveying and feeding chains shall be driven from a single source of 100 power as it is necessary that the relative speed of the chains and the relative spacing and relation of the several spurs be strictly maintained. The speed of the conveying and feeding mechanism as a whole may be 105 varied as desired by shifting the belt upon the cone pulleys 37 and 38, and the conveying and feeding devices may be stopped and started at will by the use of the friction clutch 36.

While I have described my invention in the proportions requisite for operating with a given size of float and cake, it will be evident that it is equally applicable to any other desired sizes, it being merely necessary 115 to vary the operative speeds and spacings of the various chains and the number of the saws to correspond to the sizes selected.

For purposes of illustration, I have found it convenient to show the several sets of 120 feeding and conveying chains as gear driven from a single main shaft, but the method of power distribution may obviously be varied to suit operative conditions.

Having thus described my invention it 125 will be evident that many other changes and modifications can be made therein by those skilled in the art without departing from the spirit and scope thereof as expressed in the claims and I do not wish to 130

be limited to the details herein disclosed, but

What I do claim is:

1. An ice cutting machine having, in combination, two sets of saws arranged on shafts at right angles to each other, separate means for feeding a float of ice past each set of saws in a direction parallel to the line of cut of each set, and additional means to transfer the float automatically from the first feeding means to the second feeding means by successive movements at right angles to each other and in predetermined timed relation to each other, whereby the direction of travel of said float may be changed 90° without interference of successive floats.

2. An ice cutting machine having, in combination, two sets of saws arranged on shafts at right angles to each other, separate means for feeding a float of ice past each set of saws in a direction parallel to the line of cut of each set, and additional means to transfer the float automatically from the first feeding means to the second feeding means by successive movements at right angles to each other and in predetermined timed relation to each other, said additional means comprising two separate sets of conveying devices intermediate said sets of feeding means, said two sets of conveying devices operating at right angles to each other and being each provided with float-engaging devices mounted and actuated to move in predetermined spaced relation with each other, whereby the direction of travel of said float may be changed 90° without interference of successive floats with each other.

3. An ice cutting machine having, in combination, a set of saws to which floats of ice may be presented in a continuous line, a second set of saws operating at right angles to the first set, separate means to feed the floats past each set of saws, conveying means formed in two parts, and means to drive all of said feeding and said conveying means at predetermined relative speed ratios, the first part of said conveying means being longitudinally alined with the first feeding means and being so positioned and speeded that it is effective to receive floats presented continuously from said first feeding means and to present them transversely in spaced relation to the second part of said conveying means, said second part being disposed at right angles to said first part and being longitudinally alined with the second feeding means, the two parts of said conveying

means and the second feeding means being driven in such relative speed ratios that the floats presented in spaced relation to said second conveying means will be presented in a substantially continuous line to the second feeding means and to the second set of saws.

4. An ice cutting machine having, in combination, a set of saws for cutting a square float of ice into strips, feeding means having driving devices thereon spaced apart by substantially the width of the float, conveying means operating at higher speed than said feeding means and having driving devices thereon spaced twice as far apart, a second conveying means operating at right-angles to the first conveying means and with the same speed and spacing, a second set of saws, and feeding means for said second set having the same speed and spacing as the first feeding means.

5. An ice cutting machine having, in combination, two sets of saws operating at right-angles to each other, feeding means for each set of saws, means to convey the ice from one feeding means to the other, said conveying means being made in two parts, driving mechanism, and power transmitting devices between said mechanism, said separate feeding means and said separate conveying means effective to drive said feeding means and said conveying means at predetermined relative speeds fixed in such ratios that the line of travel of the ice may be changed 90° and that the ice will pass each set of saws in a substantially continuous line.

6. An ice cutting machine having, in combination, two sets of saws mounted on shafts at right angles to each other, separate devices for feeding a float of ice to each set of saws in a direction parallel to the line of cut, a two-part conveyer for automatically changing the direction of travel of said float by 90° and for transferring the float from the first set of feeding devices to the second, and laterally spring-pressed guiding members engaging said float substantially throughout its transfer movement, and effective to prevent separation of the severed sections of the float while on said conveyer, whereby said sections are retained in fixed relation to each other.

In testimony whereof I have hereunto set my hand, in the presence of two subscribing witnesses.

RICHARD W. RICH.
